UNITED STATES PATENT OFFICE.

OLIVER E. BARTHEL, OF DETROIT, MICHIGAN.

ENGINE HEAD.

Application filed December 30, 1922. Serial No. 610,038.

This invention relates to an engine head of that class mounted on the cylinders of an internal combustion engine and adapted to admit explosive mixtures to the engine cylinders, permit of burned gases exhausting therefrom, prepare the explosive mixtures for better combustion or more perfect detonation within the cylinders or combustion chambers thereof, and control the temperature of fuel prior to being vaporized or after being vaporized and prior to being admitted to the engine cylinders.

I am aware that explosive gases or mixtures have been heated prior to being admitted to engine cylinders or combustion chambers thereof, such heating in some instances being accomplished by locating a fuel chamber or gallery on top of the engine cylinders so that walls of the chamber or gallery may be heated by conduction.

Figuratively speaking, unvaporized fuel in such a chamber or gallery is cooked or fried by being deposited on a heated wall of the chamber or gallery or conducted to hot places in such chamber or gallery. I have found that in many instances the heat is too great with a resultant loss in volumetric efficiency and loss of power. Therefore I have devised and put into practice means for regulating the temperature of the fuel chamber or gallery, said means being built into the engine head so that there is a unitary structure that may be mounted on a cylinder block similar to an ordinary cylinder head.

In addition to the temperature controlling means of the fuel chamber or gallery, I have eliminated the usual side intake manifold with a carburetor below the plane of a cylinder head, and built one or more carburetors in the fuel chamber or gallery. Distinct advantages are gained by a carburetor-in-the-head engine. First, elimination of the side manifold and a low level carburetor necessitating a lift of fuel; second, the juxtaposition of the carburetor and cylinder head insures preheating of the fuel to be vaporized; third, accessibility to the carburetor for regulating the entraining of fuel and gases; fourth, a more direct communication between the source of fuel and the engine cylinders or combustion chambers thereof, and fifth, increasing the horsepower of

an engine provided with a head in accordance with my invention.

In putting my invention into practice, I have constructed an engine head so that it may be easily and quickly substituted for engine heads now in use, and without necessarily discarding such heads the principle of my invention may be embodied in a chamber or gallery adapted to be mounted on an ordinary engine head. In either instance there is an air gallery, chamber or space serving as a variable insulator between the engine and the fuel chamber or gallery. The air chamber or gallery is adapted to have a draft induced therein, from either end of the air chamber or gallery by any suitable means, and by varying the amount of air permitted to pass through the air chamber or gallery the temperature of inflowing gas may be easily controlled. In a like manner the cooking of fuel or its preheating may be controlled.

The construction by which I attain the above and other results will be hereinafter specifically described and then claimed and reference will now be had to the drawings, wherein—

Figure 1 is a plan of the engine head, partly broken away and partly in horizontal section;

Fig. 2 is a side elevation of the same;

Fig. 3 is a plan of an engine head provided with more than one carburetor;

Fig. 4 is a cross sectional view of the engine head taken through one of the carburetors;

Fig. 5 is a longitudinal sectional view of a portion of the head taken on the line V—V of Fig. 4, and

Fig. 6 is a diagrammatic view illustrating an adaptation of my invention to an ordinary cylinder head.

The engine or cylinder head comprises a bottom wall 1 adapted to be mounted on the cylinders 2 of an internal combustion engine, and said bottom wall has combustion or compression chambers 3 corresponding in number to the cylinders of the engine. About the chambers 3 are heat disseminating ribs 4 and apertured bosses 5 to facilitate securing the head to the engine.

The top of each combustion or compression chamber 3 is formed with valve seats 6

at the inner ends of exhaust passages 7 and intake passages 8 and these passages assist in supporting an inclined bottom wall 9 co-operating with side walls 10 and 11 and end walls 12 in forming a fuel chamber 13 throughout the length and width of the engine head.

Suitably mounted on the walls 10, 11 and 12, is a cover 14 for the fuel chamber and this fuel chamber or gallery communicates with the intake passages 8, as best shown in Figs. 1 and 4.

Suitably mounted on the sides of the head are side plates 15 and 16, the former having openings corresponding in number to the exhaust passages 7 of the head. The side plates 15 and 16 cooperate with the bottom wall 1 and the inclined wall 9 in forming an air chamber or gallery 17 throughout the length and width of said head, said air chamber or gallery being interposed between the engine and the fuel gallery 13 in order that it may be used to regulate the temperature within the fuel gallery by the circulation 20 of air through the air gallery. For this purpose one of the end walls 12 of the head may be formed with a flared or funnel entrance 18 adapted to receive air, either drawn into the air gallery or forced therein, and in order that the circulation or passage 25 of air through the gallery may be controlled to regulate the heating or vaporizing of fuel in the fuel gallery 13, the opposite end of the air gallery has a conventional form of damper or throttle 19 that may be manually or automatically adjusted. For instance, the throttle may be actuated through the medium of a thermostatic device located in the fuel chamber or at a place where heated fuel 40 or air may regulate the passage of air through the air gallery or the operation of a fan or other device employed to induce a draft in the air gallery.

Since the inclined wall 9 is integral or in proximity to the combustion or compression chambers 3, it is obvious that this inclined wall will be heated by conduction and in order to prevent excessive heating the air gallery has been interposed and permits of the intake and exhaust passages 7 and 8 being cooled and the temperature within the fuel gallery regulated in accordance with the fuel to be heated or vaporized within the gallery.

The cover 14 is formed with guides 20 vertically alining with guides 21 of the inclined bottom wall 9 and the guides 20 and 21 may be provided with bushings 22 for the rods or stems 23 of intake and exhaust valve 24. These valves are of a conventional form opening into the combustion or compression chambers 3 of the head and are merely illustrative of valvular means that may be employed for controlling the supply of an explosive mixture to the chambers 3 and the

exhaust of burned gases therefrom; it being obvious that the fuel and air chambers might be associated with an engine head of the L type or other than overhead valves.

The inclined wall 9 is interrupted by a depressed portion 25 and the cover 14 is interrupted by a raised portion 26 which cooperates with the depressed portion 25 in forming a substantially cylindrical carbureter chamber 27 disposed transversely of the fuel gallery and laterally communicating therewith, as best shown in Fig. 5, said carbureter chamber having an inner conical end and an outer open end 28 extending through the side plate 16. In the open end 28 of the carbureter chamber is mounted the head 29 of a cylindrical carbureter casing 30 provided with an axial tube 31 affording an air passage 32 into the conical inner end of the carbureter chamber. The inner end of the tube 31 is flared and integral with the carbureter casing 30, thus providing a cylindrical chamber 33 about the tube 31 with the lower half of the chamber serving as a fuel basin or auxiliary reservoir. The outer end of the tube 31 is also flared, as at 34, to permit of air being readily drawn into the air passage 32 and contiguous to the outer open end of said tube is a conventional form of throttle 35 for controlling the volume of air drawn 95 into the carbureter.

The lower walls of the carbureter casing 30 and the tube 31 support a ported nozzle or fuel supply member 36 which has its lower end ported, as at 37 to communicate 100 with the basin or bottom of the chamber 33 to receive liquid fuel therefrom, and said nozzle has a vertical port 38 in which liquid fuel rises to the level of liquid fuel within the lower part of the casing 30. On the upper end of the nozzle or fuel supply member 36 is a ported lateral extension 39 axially of the passage 32 and extending into a Venturi member 40 in the inner end of the passage 32, said Venturi member forming a restricted passage about the orifice of the extension 39 so that air drawn into the passage 32, through the Venturi member 40, produces a reduction of atmospheric pressure in the ported extension 39 and withdraws liquid fuel from the nozzle or fuel supply member.

The head 29 of the carbureter casing 30 has a side extension 41 that may support a float chamber or reservoir 42 containing liquid fuel, as kerosene or gasoline, said float chamber having its bottom on a level with or slightly above the bottom of the chamber 33 so that kerosene or gasoline may flow from the float chamber 42 through an opening or passage 43 of the head 29 into the lower part of the chamber 33. With a conventional form of float controlled valve associated with the float chamber 42 a level of fuel may be maintained in the float chamber 130

corresponding to the height of the port 38 in the nozzle 36, thus providing a constant supply of fuel in the nozzle open to the fuel gallery. Since the walls of the fuel gallery 5 are subjected to heat, by conduction, it is obvious that the walls of the carburetor casting 30 will also be heated, if not by conduction by radiation of heat from the engine, and consequently the semi-cylindrical body 10 of kerosene or gasoline in the chamber 33 will be heated and placed in better condition for atomization and eventually for combustion purposes. Should the fuel not be fully atomized when leaving the inner end of the 15 air tube 31 the walls of the fuel gallery will collect any solid fuel, which will be vaporized or drain on to the inclined wall 9. If not immediately vaporized or cooked by this heated wall the solid fuel will drain to 20 the lower edge of the inclined wall and be eventually vaporized when the temperature within the air gallery is raised by retarding the flow of air therethrough.

From the foregoing it will be noted that 25 a perfectly dry gas may be obtained and uniform combustion maintained throughout the entire speed range of the engine, and since raw kerosene or fuel cannot enter the cylinders of the engine there cannot be any 30 seepage into the crank case of the engine and dilution of lubricating oils therein.

Instead of providing a special cylinder head as just described I may obtain almost as fine results by mounting a fuel gallery 44 35 on top of an ordinary engine cylinder head 45, as shown in Fig. 6, with an air space or gallery 46 between the top of the cylinder head and the bottom of the fuel gallery. If the fuel gallery 44 is not provided with a 40 set-in carburetor, vaporized fuel may be supplied to the gallery at a side or end intake connection 47, and the vaporized fuel, after being heated in the gallery, conducted to the head 45 by a manifold 48. It is obvious that 45 the air gallery 46 may be inclosed and throttled so that the degree of insulation between the head 45 and the gallery 44 may be varied to regulate the temperature within the gallery.

50 Instead of a single carburetor or tube, as shown in Fig. 3, I may equip a multi-cylinder internal combustion engine with a plurality of carburetors built into the heads 55 of the engine cylinders, and while I have herein shown and described a convenient form of carburetor, I desire to be understood that the carburetor construction is susceptible to such changes as may be necessary for different fuels, climatic conditions, and 60 cylinder heads of various designs. The same holds true for the fuel and air galleries, therefore my invention, as a whole, is susceptible to such variations as fall within the scope of the appended claims.

65 What I claim is:—

1. The combination of a cylinder head having intake and exhaust passages, a substantially horizontal air gallery above said head and about the passages of said head, a fuel gallery above said air gallery communicating with the intake passages of said head, and means controlling the passage of air through the air gallery. 70

2. The combination of a cylinder head having intake and exhaust passages, a substantially horizontal air gallery above said cylinder head and about the passages of said head, and a fuel gallery above said air gallery communicating with the intake passages of said head, said fuel gallery having an inclined bottom wall subjected to heat from the bottom of said cylinder head. 75

3. The combination of an engine cylinder, a head for the engine cylinder, said head having a fuel chamber with an inclined bottom wall adapted to be heated from the engine cylinder, and a fuel carburetor set in the fuel chamber of said head and interrupting the inclined wall of the fuel chamber and adapted to supply fuel to the chamber. 80

4. The combination of an engine cylinder, a head for the engine cylinder, said head having a fuel chamber adapted to be heated from said engine cylinder, said head cooperating with said fuel chamber in forming an air passage therebetween with means for regulating the passage of air in the air passage and the heating of the fuel chamber from the engine cylinder. 85

5. The combination of a multi-cylinder engine, a head for said engine having a fuel gallery in the top thereof and an air gallery interposed between said fuel gallery and the bottom of said head, means associated with the air gallery of said head for controlling the passage of air through the air gallery, and means associated with the fuel gallery of said head and on a level therewith for supplying fuel to the fuel gallery of the engine head. 90

6. The combination called for in claim 5, wherein the last mentioned means includes a carburetor having the greater part thereof within the engine head. 100

7. The combination called for in claim 5, wherein the air gallery and fuel gallery of said head are the full width and length of said head. 105

8. A carburetor-in-the-head engine including a fuel gallery heated from the engine and an air gallery between the engine and fuel gallery controlling the temperature in the fuel gallery, and a carburetor having portions thereof in the fuel and air galleries. 110

9. An engine head including a fuel gallery heated from the engine, and an air gallery between the engine and fuel gallery controlling the temperature in the fuel gallery, said galleries being substantially flat 115

and confined within the vertical side and end planes of the engine head.

10. An internal combustion engine having cylinders with a gallery over said cylinders adapted to supply explosive mixtures to the engine cylinders, an air tube extending into the gallery and adapted to supply air to said gallery, a fuel nozzle opening into said air tube and adapted to have fuel removed therefrom by air drawn through said air tube into the gallery of the engine, and a casing surrounding said air tube and containing fuel for said nozzle.
11. A multi-cylinder engine head, comprising superposed air and fuel galleries, with the bottom wall of the fuel gallery forming the top wall of the air gallery, a casing interrupting said galleries, an air intake tube axially of said casing communicating with the fuel gallery and cooperating

with said casing in forming a fuel chamber, and a fuel nozzle in said air intake tube communicating with the fuel chamber in said casing.

12. An engine head as called for in claim 11, and a throttle and Venturi member in said air intake tube.

13. An engine head as called for in claim 11, and a float chamber supported from the outer end of said casing.

14. An engine head as called for in claim 11, and cylinder intake and exhaust passages in the air gallery adapted to be cooled by a draft of air in said air gallery.

15. An engine head as called for in claim 11, and a throttle at one end of the air gallery regulating the flow of air in said air gallery.

In testimony whereof I affix my signature.

OLIVER E. BARTHEL.
